Filed May 3, 1963, Ser. No. 74,735

Term of patent 14 years

(Cl. D54—14)

FIG. 1.

FIG. 2.

FIG. 3.

FIG. 4.

FIG. 5.

FIGURE 1 is a side elevational view of a casing for a key duplicating machine, showing my new design;

FIGURE 2 is a top plan view thereof;

FIGURE 3 is an end elevational view thereof corresponding to the left-hand end of the machine as shown in FIGURES 1 and 2;

FIGURE 4 is an elevational end view of the right-hand end of the machine as viewed in FIGURES 1 and 2; and,

FIGURE 5 is a bottom plan view thereof.

The dominant features of my design reside in the portions shown in full lines.

I claim:

The ornamental design for a casing for a key duplicating machine, substantially as shown and described.
